Attorney.

UNITED STATES PATENT OFFICE.

BENJAMIN M. DES JARDINS, OF WEST HARTFORD, CONNECTICUT, ASSIGNOR TO
UNDERWOOD COMPUTING MACHINE COMPANY, OF NEW YORK, N. Y., A CORPO-
RATION OF NEW YORK.

COMPUTING-MACHINE.

1,369,791.

Specification of Letters Patent.

Patented Mar. 1, 1921.

Application filed June 28, 1919. Serial No. 307,391.

To all whom it may concern:

Be it known that I, BENJAMIN M. DES JARDINS, a citizen of the United States, residing in West Hartford, in the county of 5 Hartford and State of Connecticut, have invented certain new and useful Improvements in Computing-Machines, of which the following is a specification.

This invention relates to improvements in 10 computing machines, and especially to machines capable of effecting algebraic computations, that is, of adding positive and negative numbers irrespective of their relative magnitudes, and of indicating the correct 15 result, whether positive or negative.

The invention is herein disclosed as an improvement on a computing machine of the Underwood-Hanson type such as the one illustrated and described in the Patent No. 20 1,278,812, granted September 10, 1918, to Hans Hanson, but is adapted for use in connection with any computing machine having a register or totalizer comprising movable number wheels or other figure-carrying 25 elements, and means for effecting either addition or subtraction by varying the positions of said figure-carrying elements.

In the form in which the invention is herein disclosed, the end sought to be attained is accomplished in a very simple and practical manner by merely providing the number wheels of the totalizer with one set of figures to represent positive values, and a second set of figures to represent negative 35 values, and by providing indexing means for concomitantly directing attention to three rows of said figures, one of said rows comprising figures intended for one of said purposes, and the other two rows comprising figures intended for the other of said 40 purposes.

The relative arrangement of the figures of the different sets on the number wheels may be varied, but the location of the indexing 45 means will be determined by the particular arrangement selected. In the form herein disclosed, each number wheel is provided with two series of figures running consecutively from "0" to "9" in opposite directions, the figures of one series being so grouped with respect to those of the other 50 that the sums resulting from the successive additions of any digit selected from figures of one series to the two adjacent digits of

the other series will equal nine and ten, respectively. 55

Any appropriate form of indexing means for concomitantly directing attention to one figure of one series and to two figures of the other series of each denominational order 60 of the totalizer may be used. As herein disclosed, a satisfactory means for this purpose is obtained by placing the number wheels within an inclosure such as to form a shield or shutter having a portion cut away to expose the three rows of figures from which the readings are to be taken. With the figures grouped as herein disclosed, the cut away portion may constitute a single slot of such width as to expose three contiguous 70 figures on each number wheel.

From the foregoing brief description, it will be seen that the desired end is attained without the use of special carrying mechanism, mechanically-operated shutters, or 75 other complicated mechanism, thus providing a very simple and practical device which will be inexpensive to produce, and which is not dependent upon movable parts likely to get out of order and disable the machine 80 or cause it to give erroneous results.

Other features and advantages will hereinafter appear.

In the accompanying drawings.

Figure 1 is a top view of the front portion 85 of a computing machine of the Underwood-Hanson type, showing the novel relations between the figures on the number wheels and the indexing means or sight-openings in accordance with one embodiment of my 90 invention.

Fig. 2 is a section through the front portion of the machine, showing one of the number wheels in its position relative to the sight-opening, parts being omitted to 95 avoid confusion.

Fig. 3 is a diagram showing a development of the face of one of the number wheels, and showing the relative arrangement of the figures of the two series. 100

Figs. 4, 5, 6 and 7 are views of the number wheels and indexing means or sight-openings, illustrating different relative positions assumed by the number wheels to indicate various readings. 105

The invention in the form herein disclosed is applied to a computing machine having a register or totalizer 20, comprising

number wheels 21, and means, comprising rack bars 22 having teeth 23, for rotating said number wheels. The mechanism for operating the rack bars and other parts of the computing machine is fully disclosed in the aforesaid Hanson patent, and such machines are in common use. The description of the computing machine need not, therefore, be set forth in detail herein.

10 Each of the number wheels 21 is provided with one series of figures 24 for indicating positive results, and with a second series of figures 25 for indicating negative results. The figures of different series may, if desired, be differentiated from each other as by color, the series for indicating positive values being black, and the series for indicating negative values being red. This is indicated in the drawings by representing 15 black figures 24 in full lines, and negative figures 25 in broken lines.

An indexing means in the form of a shield or shutter is provided for the number wheels of the register or totalizer by placing the same within the casing of the computing machine, and providing an opening or slot 26 of sufficient width to expose three continuous rows of figures on the number wheels.

30 When using the machine with the improvement applied thereto for ordinary addition and subtraction, in which case the results will always be positive, the readings will be taken from the middle row of black numbers exposed at the sight-opening. Fig. 4 is an illustration of the figures on the number wheels which appear at the sight-opening when the machine is cleared, that is, when each of the number wheels exhibits 35 zero at the center of the sight-opening, as indicated at 27.

Starting with the machine in this condition, let it be assumed that the number 3,120,760 is to be added to the number 45 876,421 and the number 2,749,541 is to be subtracted therefrom: the result, in this instance, would be positive and would be properly indicated at the center row of figures on the totalizer, as illustrated in Fig. 5, 50 in which the reading, 1,247,640, is inclosed in broken lines at 28.

Should the machine now be operated in an attempt to subtract the number 2,109,614 from that previously accumulated in the totalizer, the correct result, which should be 55 $-861,974$, would not appear in the row of black figures exposed at the center of the sight-opening, as before, but, instead of this result, there would appear, as indicated in Fig. 6, a complementary number 999,138,026, which if added to the correct result, ignoring the minus sign, would be represented by a "1" followed by as many zeros as there are denominational orders or decimal places in 60 the totalizer. It is well known to those

skilled in the art that this will happen whenever the number to be added is larger than that previously accumulated in the totalizer and of opposite character, as when a negative number is added to a smaller positive 70 number.

It may be observed that the first figure at the center of the sight-opening, as illustrated in Fig. 6, is a black "9", and this will always be true when a negative number has 75 been added to a smaller positive number previously accumulated in the totalizer, provided the machine is not used to add or subtract numbers having as many decimal places or denominational orders as there are 80 number wheels in the totalizer. In using a machine with my invention applied thereto, I therefore arbitrarily select one having at least one more number wheel in its totalizer than the largest number of decimal places 85 or denominational orders in the numbers which it is intended to add or subtract, and assign the highest number wheel to a special purpose, that is, for use as a signal or warning to indicate whether the result is positive 90 or negative. Under such circumstances the highest number wheel will normally expose a black zero at the center of the sight-opening. This zero could never be changed to a "9" by adding positive numbers except as a 95 result of a large number of computing operations, and in no event could it be changed from "0" to "9" by adding positive numbers except by successively exhibiting "1", "2", "3" and all of the other digits up to "9". It 100 is well known, however, that it will invariably be changed immediately from "0" to "9" whenever any negative number is added to a smaller positive number previously accumulated in the totalizer. The appearance 105 of the black "9" at the center of the sight-opening on the number wheel of highest denominational order will therefore serve as a warning or signal to the operative that the result indicated by the totalizer is negative, 110 in which case the correct reading may be taken in part from the lower row of red figures and in part from the upper row in a simple and practical manner which will hereinafter be explained.

115 Referring again to Fig. 6, it may be observed that the last figure "4" of the correct result (inclosed in broken lines at 29) appears in red over the black "6" which is the last significant figure of the black row at the 120 center of the sight-opening, and that the remaining figures of the correct result (inclosed in broken lines at 30) are found in their proper denominational orders or decimal positions in the lower row of red figures. 125

Should the machine now be operated in an attempt to add, to the sum already accumulated in the totalizer, another negative quantity, as $-4,836,026$, the correct result $-5,698,000$ will again be found, as indicated 130

in Fig. 7, partly in the lower line of figures and partly in the upper line, that is, the first three figures, 569, are indicated within the broken lines at 31, and the last four figures, 5. 8000, are indicated within the broken lines at 32. It may be observed that the first figure read from the upper row is the one above the last significant figure of the row of black figures at the center of the sight-opening.

The distribution of the figures to make up the complete reading of a negative result follows a simple law which may be stated in several ways, and by the observance of 15 which the operative may, in every instance, readily obtain the correct reading with accuracy, and without making any mental computation.

One simple rule for reading the totalizer 20 may be stated as follows:

(a) Whenever a black "0" appears on the number wheel of highest order, at the center of the sight-opening, the result is positive and is directly read from the center row of 25 figures, as indicated in Fig. 5, at 28.

(b) Whenever a black "9" appears on the number wheel of highest order, at the center of the sight-opening, the result accumulated in the totalizer is negative, and 30 should be read partly from the lower row of figures and partly from the upper row of figures, as indicated in Figs. 6 and 7.

(c) The numbers to be read from the lower row of figures must always include 35 those of all denominational orders or decimal places preceding that of the last significant figure (the "6" of Fig. 6 or the "2" of Fig. 7) of the center row of black figures. Those to be read from the upper row should 40 begin with the denominational order or decimal place of the last significant figure of the row of black figures and include all figures of lower denominational orders.

The above stated rule is simple and 45 variable in its application, and could be readily mastered by an operative in a negligible space of time, after which the negative readings may be taken from the totalizer with the same degree of ease and accuracy 50 as in reading the positive results in an ordinary totalizer.

In many kinds of work, it is customary at the end of a computation to type the reading of the totalizer with the computing 55 mechanism set for subtraction in case of a positive reading and for addition in case of a negative reading. In case the correct reading has been typed, all of the dial or number wheels will be set at zero at the 60 completion of the computation, thus checking the correctness of the reading. Obviously, any error in reading a negative result would be indicated immediately by a reading other than zero upon the dial wheels 65 of the totalizer.

Variations may be resorted to within the scope of the invention, and portions of the improvements may be used without others.

Having thus described my invention, I claim:

1. In an algebraic computing machine, the combination with number wheels having figures to represent positive values and other figures to represent negative values, of means to facilitate the reading of negative 75 results comprising indexing means for concomitantly directing attention to one row of the figures intended for one of said purposes and two rows of the figures intended for the other of said purposes.

2. In an algebraic computing machine, the combination with number wheels having for each of a plurality of denominations, as units, tens, etc., figures of two differentiated series, of means to facilitate the reading of 85 negative results comprising indexing means for concomitantly directing attention to one figure of one series and two figures of the other series for each of said denominations.

3. In an algebraic computing machine, the combination with a set of number wheels, one for each of a plurality of denominations, as units, tens, etc., each having figures of two series, the figures of each series comprising a "0" and the digits "1" to "9," those 95 of one series being alternated with those of the other, and arranged in inverse order, the relative arrangement being such that the sums resulting from the successive additions of any digit of one series to its two adjacent digits of the other will equal nine and ten, respectively, of an index to facilitate the reading of negative results, said index comprising means for concomitantly directing attention to one figure of one series and to 100 the two adjacent figures of the other series 105 for each of said denominations.

4. In an algebraic computing machine, the combination with number wheels having, for each denomination, as units, tens, etc., figures of two series, those of one series being represented in black and those of the other series in red, of indexing means for concomitantly directing attention to one black figure and two red figures for each of said denominations to facilitate the reading of 110 negative results.

5. In a computing machine, in combination, a set of number wheels having one set of figures for indicating positive results and 115 a second set of figures for indicating negative results, each of said sets comprising, for each denominational order, a zero and the digits "1" to "9," inclusive, the figures of the different sets running in opposite directions, 120 and means to facilitate the reading of negative results comprising indexing means for concomitantly directing attention to one row of the figures intended for one of said purposes, and two rows of the figures intended 125 130

for the other of said purposes, the relative arrangement of the figures of the two sets on the number wheels and the relative positioning of the indexing means being such 5 that the sums which would result from the successive additions of any indexed figure of the first of said rows to the two indexed figures of corresponding denominational order in the other of said rows will always 10 equal nine and ten, respectively.

6. In an algebraic computing machine, the combination with number wheels having figures to represent positive values and other figures to represent negative values, of 15 means to facilitate the reading of negative results comprising means for concomitantly exposing one row of the figures intended for one of said purposes and two rows of figures intended for the other of said purposes, 20 while concealing the remaining figures.

7. In an algebraic computing machine, the combination with a set of number wheels, one for each of a plurality of denominations, as units, tens, etc., each having figures of 25 two series, the figures of each series comprising a "0" and the digits "1" to "9," those of one series being alternated with those of the other, and arranged in inverse order, the relative arrangement being such that the 30 sums resulting from the successive additions of any digit of one series to its two adjacent digits of the other will equal nine and ten, respectively, of means to facilitate the reading of negative results comprising a shield 35 having a sight-opening for concomitantly exposing one figure of one series and the two adjacent figures of the other series for each of said denominations, said shield also having means for concealing the remaining 40 figures.

8. In an algebraic computing machine, the combination with number wheels having for 45 each denomination, that is, units, tens, etc., figures of two series, those of one being represented in black and those of the other in red, of means to facilitate the reading of negative results comprising means for concomitantly exposing one row of black figures and two rows of red figures, while concealing 50 the remaining figures.

9. In a computing machine, in combination, a set of number wheels having one set of figures for indicating positive results and a second set of figures for indicating 55 negative results, each of said sets comprising for each denominational order a zero and the digits from "1" to "9", inclusive, the figures of the different sets running in opposite directions, and means to facilitate 60 the reading of negative results including indexing means comprising means for concomitantly exposing one row of figures intended for one of said purposes, and two rows of the figures intended for the other 65 of said purposes, to the exclusion of the

others, the relative arrangement of the figures of the two sets on the number wheels and the positioning of the means for concomitantly exposing certain of said figures being such that the sums which would result from the successive additions of any exposed figure of the first-mentioned row to the two exposed figures of corresponding denominational order in the other of said rows, will always equal nine and ten, respectively. 70 75

10. In an algebraic computing machine, the combination with number-wheels having figures to represent positive values and other figures to represent negative values, of means to facilitate the reading of negative results comprising means for determining the row of positive figures from which positive results are to be read, one row of negative figures being exposed 80 on each side of the row in which positive results are read to enable the reading of part of the negative result from one of said rows and the remaining part from the other of said negative rows. 85 90

11. In an algebraic computing machine, the combination with number-wheels having for each denomination, as units, tens, etc., figures of a positive series and figures of a negative series, of means to facilitate 95 the reading of negative results comprising means to determine the row of positive figures from which positive results are to be read, two rows of figures of the negative series being exposed so that negative results 100 may be read partly from one of said rows of negative figures and partly from the other of said rows of negative figures.

12. In an algebraic computing machine, the combination with number-wheels having 105 for each denomination, as units, tens, etc., figures of two series, those of the positive series being represented in one color, and those of the negative series in another, of means to determine the row of positive figures 110 from which positive results are to be read, two rows of negative figures being exposed so that part of a negative result may be read from one row and the remainder from the other row. 115

13. In an algebraic computing machine, the combination with number-wheels having figures to represent positive values and other figures to represent negative values, of means to facilitate the reading of negative results comprising means to indicate the row of positive figures from which positive results are to be read, and to indicate two rows of negative figures from which negative results may be read, partly from 120 one row and partly from the other. 125
